(57) **CLAIM**

The ornamental design for a broom and dustpan set, as shown and described.

DESCRIPTION

FIG. 1 is a top, front, left side perspective view of the broom and dustpan set, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is an enlarged top plan view thereof;

FIG. 7 is an enlarged bottom plan view thereof;

FIG. 8 is a bottom, rear, right side perspective view thereof; and,

FIG. 9 is a top, front, left side perspective view when the broom and dustpan set is used.

The broken lines in the drawing depict environmental subject matter only and form no part of the claimed design.

1 Claim, 9 Drawing Sheets
